FOLDING TABLE AND SEAT COMBINATION

Ruby G. Woodley, Paducah, Tex.

Application April 27, 1951, Serial No. 223,370

8 Claims. (Cl. 155—124)

1

This invention relates to a novel construction of table and seat combination having only one detachable part and the remaining elements of which are capable of being readily folded or collapsed into a compact unit which may be easily stored or transported and which may be quickly and easily arranged in an extended position to provide a plurality of seats and a table top supporting member.

More particularly, it is an aim of the present invention to provide a unit having swingably and swivelly connected parts capable of being readily latched in extended operative positions and which may be readily swung to collapsed positions with the parts in overlapping relationship to provide a long slender bundle of connected parts which may be readily stored or transported.

A further object of the invention is to provide a table and seat combination particularly adaptable for use out-of-doors for camping and picnics and which is so constructed that it is extremely efficient and durable for accomplishing its intended purpose yet is capable of being very economically manufactured and sold.

Various other objects and advantages of the invention will hereinafter become more fully apparent from the following description of the drawings, illustrating a presently preferred embodiment thereof, and wherein:

Figure 1 is a side elevational view, partly in vertical section illustrating the invention in an extended, operative position;

Figure 2 is a top plan view thereof;

Figure 3 is an end elevational view looking from left to right of Figure 1;

Figure 4 is a cross sectional view of the invention taken substantially along a plane as indicated by the line 4—4 of Figure 1;

Figure 5 is a perspective view showing the unit in an extended position and before application of the detachable table top, and

Figure 6 is a side elevational view, partly in section, showing the unit of Figure 5 in a folded or collapsed position.

Referring more specifically to the drawings, the folding table and seat combination in its entirety and as illustrated in Figures 1 and 2, includes a foldable or collapsible unit, designated generally 9 and illustrated in Figures 5 and 6 including all of the elements of the combination as illustrated in Figures 1 and 2 except the removable table top 10 and the fastenings 11, carried thereby.

The foldable or collapsible unit 9 includes an elongated base member or board 12 and a sec-

2

ondary base member or board 13 which is disposed on and suitably secured to the board 12 which extends from one end thereof to a point intermediate of the ends of the board 12. A fastening 14 having a headed upper end extends downwardly through the base members 12 and 13 at one end of the base member 12 and a similar fastening 14 extends downwardly through the base member 12 adjacent its opposite end. Said fastenings 14 are swivelly connected to intermediate portions of elongated foot members 15 which are provided intermediate of their ends with downwardly opening sockets 16 in which is accommodated a nut and washer of the fastening 14, engaging said foot member 15.

A seat leg 17, preferably of the same cross sectional size and shape as the base members 12 and 13, is connected by a hinge 18 to the upper surface of the base member 12, adjacent the end thereof disposed remote to the base member 13 and is adapted to have one end rest upon the base member 12 when the seat leg 17 is in an extended, upright position as illustrated in Figures 1 and 5. The leg 17 is also adapted to

fold against the upper surface of the base member 12 with its upper end disposed in spaced end to end relationship to the base member 13 and in substantially the same plane, as illustrated in Figure 6. An elongated bar 19, forming a seat, is connected by a hinge 20 to the leg 17, one leaf of the hinge 20 being secured to a side edge of the leg 17 and the other leaf thereof being secured to the underside of the seat 19, near one end thereof, as best illustrated in Figure 4, so that the seat may be swung to a horizontal position with its intermediate portion resting upon the upper end of the leg 17 or into an extended position parallel to said leg and outwardly of the side edge thereof to which the hinge 20 is connected. A hook 21 has its shank end swingably connected to the eye of an eye screw 22 which projects from the opposite edge of the leg 17 and said hook detachably engages the eye of an eye screw 23 which depends from the underside of the seat 19, adjacent the end thereof disposed remote to the hinge 20. The hook 21 has a shank portion formed of spaced end sections connected by a turnbuckle 24 which is threadedly connected to one of the shank sections for extending or reducing the length of the hook shank so that the hook 21 can be secured tightly to the eye 23 and nondetachably, if desired, by tightening the turnbuckle 24 after engagement of the hook with said eye. A corresponding hook 25 is swingably connected at one end thereof to an eye fastening 26

which is secured to and projects from one side edge of the base member 12 adjacent the end thereof disposed beyond the leg 17 and the opposite end of said hook 25 engages the eye of a fastening 27 which projects from the complementary side edge of the leg 17 and by means of which hook 25 the leg 17 is detachably latched in an extended, upright position.

A leg 28, of the same cross sectional size as the leg 17, is hingedly connected to the upper surface of the base member 13, adjacent its outer end, by a hinge 29 and said leg 28 has one end resting upon the upper surface of the base member 13 when in an extended, upright position. The leg 28 is shorter than the leg 17 so that the upper ends of the legs are disposed at substantially the same level when extended. The leg 28 is swingable downwardly and inwardly to a folded position upon the upper surface of the base member 13 and when so disposed terminates inwardly of the inner end of said base member 13. The leg 28 is detachably maintained in an upright position by a hook 30, corresponding with the hook 21, the shank end of which connects to the eye of a fastening 31 which projects from side edge of the base member 12 and the opposite end of which hook 30 detachably engages the eye of a fastening 32 which projects from the complementary side edge of the leg 28.

An elongated bar forming a seat 33 is provided intermediate of its ends and in its underside with a downwardly opening recess 34 normally closed by a plate 35 which is secured to the underside of the seat 33 by fastenings 36 and which is provided intermediate of its ends with an opening 37 to receive the shank of a headed bolt 38, the head of which is disposed in the recess 34 and the shank of which is provided with a right angular bend adjacent said head. The recess 34 is of sufficient length and width to accommodate the portion of the bolt shank disposed between the bend and head. The opposite end of the bolt shank extends downwardly through a longitudinal bore 39 in the upper portion of the leg 28, in which it is loosely disposed, and terminates in a socket 40 which opens outwardly of the outer side of the leg 28. A nut 41 is loosely disposed in the socket 40 and threadedly connected to the terminal of the bolt shank and is retained thereon by a cotter pin 42. The bend of the bolt shank is disposed sufficiently above the upper or outer end of the leg 28 so that the opening 37 of the plate 35 can slide along the bolt shank from its position against the bolt head, as illustrated in Figure 6, to a position against the upper end of the leg 28 to enable the seat 33 to slide and turn relatively to the bolt 38 and thus be moved from its position of Figures 3 and 5 upon and crosswise of the leg 28 to its position of Figure 6 longitudinally of said leg. A pair of corresponding braces 43 are swingably connected at corresponding ends thereof to the outer or upper side of the leg 28 each by a nut and bolt fastening 44 and the opposite, free ends of said braces 43 are detachably connected to the seat 33, adjacent the ends thereof, each by a bolt and wing nut fastening 45 which extends through and projects from one side edge of the seat. The braces 43 project upwardly and outwardly in diverging relationship relatively to one another when engaged by the fastening 45 and function to rigidly support the seat in a horizontal position on the upper end of the leg 28 and are detached therefrom to assume positions longitudinally of the leg 28.

when the leg and seat are moved to collapsed, folded positions, as illustrated in Figure 6.

A table leg 46 preferably of the same cross sectional size and shape as the seat legs 17 and 28, but longer than either of said legs, is connected by a hinge 47 to the base member 13, one leaf of the hinge being secured to the inner end of the base member 13 and the other leaf thereof being secured to one side of the leg 46 to permit the leg to assume an upright position with its lower end resting on the upper surface of the base member 13 or a collapsed position above the leg 17, as illustrated in Figure 6. A table top supporting bar 48, corresponding in construction to the seat 33 including a recess 34a, a bottom plate 35a, secured by a fastening 36a and having an opening 37a, is mounted on the upper end of the leg 46 and is connected thereto by a bolt 38a, nut 41a and cotter pin 42a, corresponding to the parts 38, 41 and 42, and so that the table top supporting bar 48 may move from a position resting on the upper end of the leg 46 to a position against the outer side thereof, as illustrated in Figures 4 and 6. The leg 46 is also provided with a socket 40a opening outwardly of one side thereof to accommodate the nut and cotter and has a longitudinal bore 39a for loosely receiving a part of the bolt shank. A pair of braces 43a is connected at corresponding ends thereof by fastenings 44a to the side of the leg 46 which constitutes its upper side when folded and the opposite ends of said braces 43a are detachably connected by bolt and wing nut fastenings 45a to the bar 48 beyond the ends of its recess 34a.

The bar 48, adjacent its ends, is provided with bores 49 extending therethrough from top to bottom thereof to receive the shanks of the fastenings 11 which depend from the table top 10 and extend downwardly through said bores 49.

The fastenings 11 are provided with wing nuts for securing the fastenings to the bar 48 and to detachably secure the table top 10 upon the bar 48. As seen in Figure 4, the heads of the fastenings 11 are countersunk in the upper surface of the table top 10.

The base member 13, between the legs 28 and 46, is provided with a recess 50 opening outwardly of its upper side to accommodate spare items of hardware employed with the table and seat combination 8 and which have been previously described and which are not disclosed in the recess or storage chamber 50. The upper end of the recess 50 is closed by a cover plate 51 which seats in a recess 52 in the upper surface of the member 13 and which surrounds the chamber 50. The cover plate 51 is provided with depending resilient flanges 53 which yieldably bear against the end walls of the chamber 50 to retain the cover plate in an applied position.

The erection of the table and seat combination 8 as illustrated in Figures 1 to 4 is considered obvious from the preceding description and it will be readily apparent that each of the seats 19 and 33 provide a support on which a user of the apparatus 8 may be seated in a convenient position for use of the table top 10 as a dining table or for any other purpose. The foot members 15 by being disposed crosswise of the base 12 will provide an adequate support for the structure 8 and are adapted to rest on any suitable supporting surface such as the ground. When it is desired to collapse the structure 8 for storage or transportation, the wing nuts of fastenings 11 are first removed so that the table top 10 may be detached after which the braces 43 and 43a are

disconnected from the seat 33 and bar 48, respectively. The hook 21 is disconnected from the eye 23 and the seat 19 is swung to its position of Figure 6 after which the hook 25 is disconnected from the eye 27 and the leg 17 and seat 19 are then swung to their collapsed positions of Figure 6. A hook 54, corresponding to the hook 25, is swingably connected at its shank end to an eye fastening 55 which projects from one side edge of the base member 13 and which is detachably connected at its opposite end to the eye of a fastening 56, which projects from the complementary side edge of the leg 46, is then disengaged from the eye 56 to permit the leg 46 to be swung downwardly to substantially a horizontal position above the leg 17 and after the bar 48 has been swung to its position of Figure 6 relatively to the leg 46. The hook 30 is then disengaged from the eye 32 and the leg 28 is then swung downwardly to a position resting upon the base member 13 and substantially parallel thereto, after the seat 33 has been swung and slid to its position of Figure 6. The foot members 15 are then swung to positions beneath and longitudinally of the base member 12 and the unit 9 as thus collapsed, and as seen in Figure 6, may be conveniently carried, stored or transported and the various components thereof may be retained in their positions of Figure 6 by suitable rope or tie means, not shown, which may be secured therearound.

Various modifications and changes are contemplated and may obviously be resorted to, without departing from the spirit or scope of the invention as hereinafter defined by the appended claims.

I claim as my invention:

1. A combination folding table and seat structure comprising an elongated base member having an elevated surface extending from intermediate of the ends of the base member to one end thereof, a seat leg swingably connected to the base member adjacent its opposite end for swinging movement between an upright and a horizontal position, said seat leg being swingable inwardly toward a horizontal position and terminating in spaced relationship to the elevated surface of the base member when in a horizontal, collapsed position, a table leg swingably connected to the elevated portion of the base member and supported in an upright extended position thereon and in a horizontal, collapsed position above said seat leg when folded, and a second seat leg swingably connected to the elevated surface adjacent the end thereof remote to the table leg for movement between an upright position resting on the elevated surface and a horizontal position on the elevated surface and in spaced relationship relatively to said table leg, bars slidably and swivelly connected to the upper ends of the table leg and second seat leg and resting on the upper ends of said legs and crosswise thereof when the legs are in upright extended positions, means for releasably retaining said bars in horizontal positions on the upper ends of said legs, said bar of the table leg forming a table top support and the bar of the second seat leg forming a seat, said bars being swingable to folded positions against the upper sides of said legs when the legs are swung downwardly to collapsed positions, and a bar hingedly connected to the first mentioned seat leg and swingable between an operative position on the upper end of and transversely of said first mentioned seat leg and an inoperative position against one side edge of said first mentioned seat leg.

2. A combination table and seat structure comprising an elongated base, seat legs hinged to the base adjacent each end thereof and disposed to rest upon and be supported by the base when in upright positions, a table leg hinged to an intermediate portion of the base and having a lower end resting upon the upper surface of the base when the table leg is in an upright position, the upper surface of a portion of the base being disposed below the level of the upper surface of another portion of the base and having one of said seat legs hinged thereto to fold against said first mentioned upper surface portion, said table leg being disposed over said seat legs when said legs are disposed in folded positions substantially parallel to the plane of the base, said other seat leg being hinged to the last mentioned surface portion of the base and being disposed in substantially a horizontal position thereagainst when in a collapsed position and in spaced relationship relatively to the table leg, a bar forming a seat resting on the upper end of each seat leg and disposed transverse to the base when the seat legs are in extended positions, the bar of the first mentioned seat leg being hingedly connected to a side edge thereof and being disposed outwardly of said side edge and to one side of the base and table leg when the legs are in folded or collapsed positions, the seat of said last mentioned seat leg being slidably and swingably connected to the leg and movable to a folded position against the upper side thereof when the last mentioned seat leg is in a folded position, and a table top supporting bar mounted on the upper end of the table leg when the latter is in an extended position and disposed crosswise of the base, said table top supporting bar being slidably and swingably connected to the table leg to fold against the upper side thereof when the table leg is in a collapsed position above the first mentioned seat leg.

3. A combination table and seat structure as in claim 2, and a table top detachably connected to the table top supporting bar and supported thereon when the table leg is in an upright position and the table top supporting bar is resting on the upper end thereof.

4. A combination table and seat structure as in claim 2, and an elongated foot member swivelly connected to the underside of each end of the base and swingable from an extended, operative position transversely to the base to an inoperative position beneath and longitudinally of the base.

5. A combination table and seat structure as in claim 2, and brace members swingably connected to the legs and detachably connected to the bars for rigidly supporting the bars in operative positions on the upper ends of the legs and transversely of the base.

6. A table and seat structure as in claim 2, and brace members swingably connected to the base and detachably connected to the legs for rigidly maintaining the legs in upright positions and with the lower ends of the legs resting upon the upper surface of the base.

7. A table and seat structure as in claim 2, and brace members swingably connected to the base and detachably connected to the legs for rigidly maintaining the legs in upright positions and with the lower ends of the legs resting upon the upper surface of the base, each of said brace members including spaced shank portions connected by a turnbuckle for varying the effective length of the brace.

8. A combination table and seat structure as in claim 2, each of the bars of the table leg and last mentioned seat leg having a recess formed therein provided with a restricted opening in the underside of the bar, an elongated fastening having one end swivelly disposed in the supporting leg of the bar and projecting from the upper end thereof, said fastening having a right-angularly bent portion above the supporting leg terminating in a fastening head, the fastening head being disposed in the bar recess and the shank portion of the fastening on either side of the bend thereof being slidable through the restricted opening of the recess for positioning the bar with its intermediate portion against the upper end

of the leg or with one end thereof disposed against a side of the bar.
